UNITED STATES PATENT OFFICE.

MARTIN B. JACOBSON, OF BLAIR, NEBRASKA.

SPARK-PLUG.

1,371,488.

Specification of Letters Patent. Patented Mar. 15, 1921.

Application filed May 13, 1919. Serial No. 296,857.

To all whom it may concern:

Be it known that I, MARTIN B. JACOBSON, a citizen of the United States of America, residing at Blair, in the county of Washington and State of Nebraska, have invented 5 certain new and useful Improvements in Spark-Plugs, of which the following is a specification.

My invention relates to electric spark 10 igniting devices, for internal combustion engines in which electrodes are permanently separated in the combustion chamber of the engine to produce a jump-spark by a current of electricity of high electromotive 15 force, and among the most important objects of my invention are:

First. To shape and dispose the electrodes so as to form a spark gap of the greatest possible width within a limited area and 20 at the same time conserve a uniform length of gap throughout such width; it being understood that the length of the gap is the distance or space between the two electrodes and the width is the distance at right angles 25 thereto throughout the uniform space or gap; although such gap may be, as intended and curved in this case, much wider than the length thereof.

Second. To facilitate the use of mica insulation in both high pressure and low pressure fuel combustion chambers, by placing the spark gap remote from the insulation of 30 the shank of the power electrode and interposing a fender or bar between said gap and the inner end of said insulation.

Third. To control and utilize the movement of gases to and fro, into and out of the shell of the seated plug, to scour the opposed sparking edges of the electrodes 40 that form the gap, and thereby prevent the fouling of said edges by accumulations of oil and soot or carbon.

Fourth. To not only protect the supports 45 of the electrodes against warping and charing by the effects of intense heat, but to place them in such relative positions as to bring the plane of a wide curved gap where it will be least varied by such warping as is unavoidable, or by mechanical disturbances in assembling, adjusting or transporting and marketing the completed spark 50 plugs.

Fifth. To produce a spark plug adapted 55 to be used in either high or low pressure cylinders without change of structure or adjustment.

I attain these objects, with others more particularly hereinafter set forth, by the mechanical parts and peculiar arrangement thereof, as illustrated by the accompanying 60 drawing in which—

Figure 1 is a vertical central section of the assembled device, taken on the dot and dash line 1 and 1 of Fig. 2, especially illustrating the relative positions of the electrodes and the adjacent chamber within the mouth of the seating shell; and Fig. 2, an inner end or lower end view, being the 65 electrode or sparking end of the plug.

The power electrode consists of the disk 70 3, which is an axially disposed integral terminal part of its supporting conductor rod 4. The conductor rod 4 is seated axially through the insulating plug or core 5 and has its end opposite to the disk threaded 75 to receive fastening nuts; also with the terminal nut to serve as a binding post for connection with the power current line in the usual manner, as will be readily understood by observing Fig. 1. The insulation core 80 is in a like usual manner concentrically seated in the outer end of the exteriorly threaded seating-shell 6, by which the plug is inserted through the walls of and into the explosion chamber of an engine. The 85 conductor rod is adjusted endwise to bring the sparking face of its terminal disk electrode substantially in a plane agreeing with the inner end or rim 14 of the shell 6. In this position the disk occupies a central concentric portion of the mouth of a chamber 13 between the disk and the inner end of the insulation core 5 and within the inner end of the shell. This shapes said mouth to the form of an annular space 15 between 90 the periphery of the disk electrode and the inner rim of the shell, and reduces the area of cross section of the mouth to much less than that of the chamber 13 surrounding the rod above the disk electrode. 95

The ground electrode consists of a single 100 piece of wire, of any desired metal. A central portion of the wire is bent to form the arc 7 of curvature substantially agreeing with the periphery of the disk electrode 105 and subtending nearly a complete circle, as shown in Fig. 2. Adjacent to the ends of this central arcuate looped section, the reverse bonds 11 and 11 are made to dispose the supporting leg portions 8 and 8 standing divergently outward to broaden the foothold or base-space between the attach- 110

ing feet 9 and 9. These foot ends 9 and 9 are bent to stand upwardly at right angles to the plane of the arcuate section, reversely curved bends and outwardly divergent supporting legs; and are seated and fastened in longitudinal perforations in the rim 14 of the shell, to support the arcuate section in a plane parallel with but spaced axially away from the face of the disk electrode. 10 This forms the spark gap 10 extending in curved width nearly the whole circumferential distance around the edge of the face of the disk electrode and in longitudinal spacing therefrom. The reverse curve bends 15 lying in the same plane as the arcuate central section, the opposite terminal or side edges of the gap occur between these bends and the angle edge 12 of the discal electrode above; the reversely curved bends 20 being spaced apart a greater distance than the length of the spark gap.

Starting by the use of a new plug, with ordinary conditions of construction and the electrodes reasonably clean, the first sparks 25 occur at one or the other of the two points where the reverse curves 11 and 11 cross outwardly under the angle 12 at the outer edge of the face of the discal electrode: the side edges of the spark gap. As the changing 30 conditions of temperature, fouling by soot or oil and changes wrought in the character of the metal, by use and age, take place, the point of occurrence of spark shifts about in the width of the gap, obviously 35 always jumping at the place of least resistance. This constant irregular shifting of the point of sparking throughout the great width of the gap and around the outer edge of the discal electrode results in advantages 40 as follows:

The open looping curvature of the ground electrode leaves a large central field of the face of the discal electrode unobstructed, so that explosion of the fuel mixture occurs 45 within this ring as quickly as around the outer or opposite side of the gap. The oft changing of position of initial ignition around this circle, changing the direction of the start of explosion, has a scouring effect 50 that keeps the face of the disk clean. Simultaneously a scouring effect on the inner surface of the curved wire electrode results from this shifting about of the point of initial ignition and explosion. Charring 55 of the electrodes is prevented as is also warping, because if any part of either attains a temperature above the other portions, the point of sparking and initial ignition shifts and thereby the temperature of 60 different parts of the electrode is nearly or quite temporarily equalized. And this variation of temperature causing alternate expansion and contraction, that shifts about to different parts of the electrodes, tends to 65 break up and loosen incrustations that may

form thereon. The scouring action on the sparking lines of the electrodes is further facilitated as follows:

The discal electrode as placed shapes the annular strictured mouth 15 to lie around outside of and adjacent to the curved spark gap and curved edges or spark lines of the electrodes. As the pressure is varied in the explosion chamber of the engine: by the return stroke of its piston, the release of 70 pressure by the exhaust and the force of the explosion of the fuel mixture, there is produced rapid forceful alternately back and forth currents of gases and fuel mixture through this mouth; caused by the normal 75 tendency of the contents to assume an equal pressure throughout the connected chambers. These forceful vibratory currents through the mouth have an efficient abrading action on the peripheral surfaces of the 80 electrodes.

The disposition of the electrodes as above set forth, and shown in the drawing, whereby all are well retired within or close to the chamber of the shell, avoiding isolated 90 and far projecting parts in the explosion chamber, in connection with the cooling effects of the alternating gas and fuel currents through the surrounding mouth, prevents the electrodes from becoming super- 95 heated to the extent of causing preignition of the fuel mixture. This adapts this spark plug to effective use in high pressure fuel-mixture-chamber engines, as well as in those of ordinary low pressure, without change of 100 structure or adjustment.

It is obvious that the broad power electrode as arranged to stricture the mouth of the chamber in the shell, to a great extent shields the well retired inner end and body 105 of the insulator core 5; thereby preventing it from being coated with lubricating oil thrown into the explosion chamber by the engine piston; thereby adapting the device for the use of mica washer insulation cores 110 for engines of high pressure ignition chambers. That the opposite halves of the wire ground electrode each consists entirely of bends of the wire made in an opposite direction to that of the other half and equal reverse 115 bends in like reverse positions in opposite halves; by this means any tendency of the heating to correct the set in the metal wire, caused by the bending in shaping the electrode, is exactly balanced in the opposite halves of the electrode and it therefore does not lose its shape in use. And the curved arcuate or looped portion 7, doubtless least apt to be distorted at its center or vertex, where least sparking occurs, lies as an 120 integral rigidly connecting brace between the opposite halves and at the point farthest removed from the rigidly seated feet. Further, the broad-spaced base of attachment, the feet 9 and 9 and angularly disposed legs 125

8 and 8, makes certain the connection and security of attachment and braces the ground electrode against any tendency to lateral displacement. As shown, the divergent legs 5 8 and 8, the only and short portions of the wire that are not bent in shaping the electrode, are disposed across the annular stricture 15 of the shell chamber 13, where they are constantly cooled by the alternating fuel and air and gas mixture currents 10 passing therethrough. That, any warping of the power electrode supporting rod, or turning or shifting it in its insulatory support, has little effect on the discal 15 electrode, other than to move it edgewise in its set discal plane, not materially modifying the uniform length of the gap at any point throughout its circular width.

I claim:

20 In a spark plug, a tubular seating shell, a tubular insulating core seated axially in said shell with its inner end spaced outwardly from the inner end of the seating shell, a conductor rod disposed axially

through said insulating core, a discal electrode of less diameter than the bore of said shell disposed concentrically on the inner end of the conductor rod and flush with the inner rim of said seating shell to partly inclose a chamber therein and form an annular mouth open inwardly from said chamber, in combination with an opposed ring-shaped electrode of diameter substantially equal to said discal electrode and spaced inwardly from the edge thereof to form a spark gap of less length than the width of said annular mouth and of width nearly equal to the whole circumference of said discal electrode, said ring electrode divided at one side by a space only a little wider than the length of said spark gap, and integral supporting legs disposed divergently from the ring at opposite sides of said space and having outwardly-angled feet seated in the rim of the seating shell.

In testimony whereof I hereunto affix my signature.

MARTIN B. JACOBSON.
